UNITED STATES PATENT OFFICE.

GEORGE RICHARD SCHUELER, OF KINGSTON-UPON-HULL, ENGLAND.

CONSTRUCTION OF SHIPS.

1,152,229.

Specification of Letters Patent. Patented Aug. 31, 1915.

Application filed March 15, 1915. Serial No. 14,349.

To all whom it may concern:

Be it known that I, GEORGE RICHARD SCHUELER, a citizen of the United States, but at present residing at Kingston-upon-Hull, 5 England, have invented certain new and useful Improvements in or in connection with the Construction of Ships; and I do hereby declare the following to be a full, clear, and exact description of the invention, 10 such as will enable others skilled in the art to which it appertains to make and use the same.

This invention relates to improvements in or in connection with the construction of ships, and more particularly of large ocean-going ships, or "liners" as they are very generally called, which are intended to carry a large number of passengers, and the object of my invention is to so construct such 20 ships that they will be practically unsinkable.

In carrying out my invention, I construct the interior of the ship, or a suitably large portion of the same, in such a way that it is 25 composed of, or is provided with a series, or a number of series of air pockets, chambers or sub-divisions, the means of entrance to and exit from which are from below, whereby, in case of damage being done to the hull 30 of the ship, water can only fill those chambers or sub-divisions actually damaged, it being prevented from rising in the other chambers or sub-divisions to any material extent owing to the air therein.

As an example of one mode of carrying my invention into effect, I arrange the 35 cabins, state-rooms and other apartments of the ship in units or groups, the admission to each chamber or sub-division being by 40 means of a staircase or the equivalent leading into the bottom of the chamber or sub-division comprising the group of cabins or the like, each chamber or sub-division should 45 water enter the ship and rise to the level of the chamber or sub-division, forming a closed air-tight pocket of the ship so far as such chamber or sub-division is concerned. That is to say, the upper part of a 50 chamber or sub-division which comprises say for example, a series of cabins, always 55 contains, unless broken up or fractured, sufficient air to prevent water from rising therein through the opening in the form of the staircase or the like by which access is obtained to such chamber or sub-division,

beyond a very limited level, the quantity of water which could enter the chamber or sub-division not being sufficient to cause drowning of the occupant or occupants, the space containing air remaining above the level of 60 the water which might happen to enter allowing ample space for breathing and for free movement of the occupant or occupants.

The staircase leading up to each chamber or sub-division is connected with a corridor 65 or passage running by preference in a longitudinal direction, said staircases being closed at the sides to prevent air escaping at the sides thereof, and each main corridor or passage has a staircase or the equivalent, 70 or more than one, leading to the deck or decks above and to the deck or decks below, with the exception of the lowest corridor or passage which has a staircase or the equivalent leading to the deck or decks above only, 75 thereby allowing of easy access to the upper or top deck from all the corridors or passages and consequently from all the chambers or sub-divisions.

Each of the chambers or sub-divisions is 80 connected with any suitable source of air supply, as for instance, by a pipe or pipes connected with an air pump suitably situated but preferably on the upper deck of the ship whereby in case of necessity fresh 85 air can be pumped into each chamber or sub-division, the air so supplied not only providing a fresh supply of air for the occupants of the chambers or sub-divisions, but being, if desired, employed for driving the water 90 out of the chambers or sub-divisions should it enter the same. Consequently by injecting air into the chambers or sub-divisions, the water can be kept down or driven entirely out of the chambers or sub-divisions. 95

Having thus stated broadly the object and nature of my said invention, I will now proceed to describe the same with reference to the accompanying two sheets of drawings which illustrate, by way of example only, 100 my invention applied to the cabins or like apartments of a large ship, Figure 1 of which drawings represents a cross section of part of a ship provided with my improvements, the upper structures of the ship being omitted. Fig. 2 is a longitudinal view of a portion of the ship taken on the line 1—2 of Fig. 1. Fig. 3 is a plan view taken on the line 3—4 of Fig. 1; and Fig. 4 is a transverse section through one of the main corridors 105 110

showing the steps down to the corridor and the steps therefrom leading up to the corridors in which are the cabins or the like to which access is had from such main corridor. Fig. 4 is drawn to a larger scale than the preceding figures.

Referring to the drawings, A, A¹, A², A³, indicate four main corridors or passages one above the other. B and C corridors or passages at each side of and as shown in the drawings, parallel with the main corridors or passages, there being a corridor or passage at each side of each main corridor or passage.

D, D¹, D² and D³ are four main staircases from the upper deck of the ship to the four main corridors or passages, and E, E¹, E², E³, E⁴, E⁵, E⁶ and E⁷ are eight staircases leading from the main corridors or passages A, A¹, A², A³ to the corridors or passages B and C running parallel with such main corridors or passages, the doors by which admission to the cabins or apartments is obtained being in the corridors or passages B and C. It will thus be seen that to reach the cabins or apartments in the corridors or passages B and C parallel with the main corridor A from the upper deck, a person would have to go down the main staircase D to the corridor or passage A and then up one of the short staircases E or E¹ to the corridor B or C depending upon which of these corridors or passages the cabin or apartment he required to reach is situated in. Similarly if he desired to reach a cabin or apartment in either of the corridors or passages B, C parallel with the main corridor or passage A² he would go down the main staircase D³ to the main corridor or passage A³ and then up one of the short staircases E⁶ or E⁷ leading to the corridors or passages B or C parallel with the main corridor A² depending upon which of these corridors or passages B, C the cabin or apartment he required to reach is situated in.

The cabins or apartments are arranged in groups each of which forms a sub-division of the ship, each group or sub-division being shown as comprising nine cabins or apartments marked 1, 2, 3, 4, 5, 6, 7, 8, 9 in Fig. 3, the transverse walls, indicated by the letter F, of each sub-division, extending across the corridors or passages B and C from which access is had to the cabins or apartments in such sub-division, whereby each corridor or passage B and C is divided into a number of inclosed portions to which access can only be had by means of the side staircases leading upwardly from the main corridors or passages, a separate side staircase such as E, E¹ being provided for each portion of each corridor or passage B, C.

G indicates an air pipe connected with a suitable source of air supply which may be an air pump or the like situated on the up-

per deck or other suitable part of the ship, and g, g¹ are branches of such pipe which deliver the air into the corridors or passages B and C preferably under the staircases leading from the main corridors or passages to the said corridors or passages B and C.

H indicates the doors of the cabins or apartments.

My improvements are applicable to practically all parts of the ship, but especially to the storage compartments, state-rooms, cabins and the like, the application to which or to a material part of which would be sufficient to provide the necessary air space to prevent the ship from sinking in case of collision, or of the ship being damaged in such a way that water would be liable to enter the ship.

With my improvements in the construction of the interior of ships, should any portion of the shell of the ship be damaged, say for instance as a result of a collision with another ship, or with an iceberg, wreckage or the like, only those air-tight sub-divisions which are actually ruptured will fill with water. Each undamaged sub-division would contain sufficient air to prevent water from rising therein beyond a very limited level, consequently as the interior of the ship is composed of several series of these sub-divisions, the quantity of water which would enter these sub-divisions would be very small indeed compared with the quantity of air compressed in the sub-divisions by the water admitted. Consequently not only would the ship be sufficiently buoyant to float (assuming of course that the port holes were closed, a precaution as will be understood which would naturally be taken) but there would be sufficient air in each chamber or sub-division of the ship to keep the occupants therein alive. The occupants of the compartments are rescued in any convenient way, upon beaching the ship, or otherwise preventing it from sinking. My improvements possess the further advantage that they will have the effect of considerably reducing the liability of fire spreading throughout the ship should one break out.

I claim:—

1. A ship provided with compartments arranged in groups upon the same floor level, each group having a separate entrance from below its floor level, whereby air is retained in the compartments comprised in said group when the compartments of another and similar group are flooded.

2. A ship provided with compartments arranged in groups upon the same floor level, each group having a separate entrance from below its floor level, whereby air is retained in the compartments comprised in said group when the compartments of another and similar group are flooded, and

means for forcing air into each group of compartments independently of the other groups.

3. A ship provided with a main corridor, 5 an auxiliary corridor arranged above the level of the top of the main corridor and communicating with it by a passageway, and compartments arranged in a group at the floor level of the auxiliary corridor and 10 having their entrances through it.

4. A ship provided with a main corridor, auxiliary corridors arranged above the level of the top of the main corridor and each 15 communicating with it by a separate passageway, and compartments arranged in groups on the same floor level as the auxiliary corridors and communicating with them.

5. A ship provided with a series of main

corridors arranged one above another, and 20 each provided with a separate passage having its entrance arranged above the level of the top of the uppermost main corridor, auxiliary corridors arranged on the same floor levels as the main corridors, each auxiliary corridor being provided with an entrance passage which connects it with the main corridor of the floor next below it in the series, and compartments arranged in groups and communicating with the auxiliary 25 corridors on the same floor levels with them.

In testimony whereof I affix my signature, in presence of two witnesses.

GEORGE RICHARD SCHUELER.
